WOOD NEWSPAPER MACHINERY CORPORATION, OF NEW YORK, N. Y., A CORPORA-
TION OF VIRGINIA.

MACHINE FOR COOLING STEREOTYPE-PLATES.

1,134,799.

Specification of Letters Patent.

Patented Apr. 6, 1915.

Original application filed September 28, 1908, Serial No. 454,972. Divided and this application filed April 22, 1910. Serial No. 557,107.

To all whom it may concern:

Be it known that I, HENRY A. WISE WOOD, a citizen of the United States, residing at New York, in the county of New York and 5 State of New York, have invented a new and useful Machine for Cooling Stereotype-Plates, of which the following is a specification.

This is a division of my application for 10 patent on a machine for finishing and cooling stereotype plates, filed Sept. 28, 1908, Serial No. 454,972.

This invention relates to machines for cooling stereotype printing plates.

15 The principal objects of this invention are to provide a means and a method whereby the plate will be cooled by water on its inner or non-printing side, to protect the printing side from the cooling water so as to avoid 20 the necessity of drying the printing surface before the plate goes to the press; and generally, to improve and simplify the construction and operation of stereotype plate cooling machines.

25 Further objects and advantages of the invention will appear hereinafter.

Reference is to be had to the accompanying sheet of drawing in which—

Figure 1 is a side elevation of a gravity 30 shaving machine constructed in accordance with the present invention, and Fig. 2 is a longitudinal sectional view of the same with certain parts omitted.

Although this invention is not limited to 35 the gravity type of shaving machines, it is particularly adapted thereto, and is shown as applied to that type. The machine is illustrated as embodying a frame 10 having an inclined top provided with a 40 horizontal receiving table 11 at one end, and having an inclined run way formed by rollers 12 arranged on an incline for receiving the edges of the plates from the table 11. Located between these rollers is a 45 fixed saddle 13 over which the plates move along over the longitudinal shaft 14 of the machine. The saddle 13 has a projection or

guard extending up from the lower end substantially fitting the interior of an unfinished plate to protect the operator who places 50 the plate in position from a cam which is located just beyond the guard, but is not shown in the drawings. As the shaft 14 revolves the plate slides down the incline by gravity into the shaving arch 21, where it 55 rests on rollers 22. Here the plate is shaved and preliminarily cooled as in my above mentioned original patent. As the plate has had at the most only a preliminary cooling in the hollow arch, to and from which water 60 flows through pipes 62, it has now to be fully cooled.

In order to prevent the wetting of the printing surface of the plate, and do away with the difficulty of drying the face of the 65 plates thoroughly, the improper performance of which operation injures the rollers of the press, the following mechanism is provided.

Surrounding the shaft 14 is a hollow semi- 70 cylindrical cooling saddle 63 connected with a source of water supply by means of a series of pipes 64 controlled by a valve 60. The outer convex surface of this saddle is provided with perforations 65 and with a series 75 of rifle grooves 66 running substantially horizontally, over which the water discharged from the inside runs in continuous unbroken streams, without producing a spray. Thus the sides of these grooves constitute means for preventing the water from 80 touching the printing surface. The water discharged from the cooling saddle passes down through the bottom of the machine where it is caught and discharged through a 85 pipe 67. On the driving shaft 68 is a worm 78 operating a worm wheel 79 on the shaft 14. This worm is located in an oil casing 69. The end of the shaft 14 is shown as provided with an internal gear 70 meshing with 90 a gear 71 on a shaft 72 journaled to rotate in the frame and provided with brackets 73 thereon carrying a rotary drying brush 74 for the interior of the plate. The sup-

porting rolls continue to the bottom of the frame, and the plate brings up against a stationary stop 75 and is removed from the machine by hand or, in the absence of the stop, may be discharged on a table or truck located at the end of the machine.

It will be understood of course that various shaving, trimming and other finishing means will ordinarily be employed with this machine. They are not shown herein as they are now well-known in the art and they can be applied easily to this machine in several ways.

While I have illustrated and described a preferred embodiment of the invention, and shown it as applied to a particular type of machine, I am aware that many modifications can be made herein and that it can be applied to many other types of machine without departing from the scope of the invention as expressed in the claims. Therefore I do not wish to be limited to all the features of construction shown, but

What I do claim is:—

25 1. In a machine for finishing stereotype printing plates, the combination of a finishing means, and means supported adjacent thereto for directing water against the backs of the plates to cool them, and for preventing the passage of the water against the printing surfaces of the plates.

30 2. In a machine for finishing stereotype printing plates, the combination of a finishing means, and means supported adjacent thereto for directing water along the backs of the plates in unbroken streams to cool them, to prevent the passage of the water against the printing surfaces of the plates.

35 3. In a stereotype plate finishing machine, the combination of a frame, a hollow semi-cylindrical cooling device located thereon, along which plates can be fed with their inner sides in close proximity to the convex surface thereof, and means for forcing unbroken streams of water through said cooling device against the non-printing sides of the plates.

40 4. In a stereotype plate machine, the combination of a frame, a hollow cooling device located thereon, means for supporting plates on said cooling device with their inner sides in close proximity to the convex surface thereof, and means for forcing unbroken streams of water through said cooling device against the non-printing sides of the plates.

45 5. In a machine of the character described, the combination of a semi-cylindrical cooling device having a perforated rifled upper surface, means for directing a cooling fluid through said perforations and along the rifled surface, and means for supporting plates on the cooling device with their non-printing surfaces in close proximity thereto.

50 6. In a machine of the character described,

the combination of a cooling device having a perforated rifled upper surface, means for directing a cooling fluid through said perforations and along the rifled surface, and means for supporting plates on the cooling device with their non-printing surfaces in close proximity thereto.

7. In a machine of the character described, the combination of a frame, a cooling device having a perforated upper surface, means for conducting a cooling fluid through said perforations and along the surface, means for supporting plates on the cooling device with their non-printing surfaces in close proximity thereto, and means carried by the frame for receiving the water discharged from said cooling device.

8. In a machine of the character described, the combination of a frame, a semi-cylindrical cooling device having a perforated rifled upper surface, means for conducting a cooling fluid through said perforations and along the rifled surface, means for supporting plates on the cooling device with their non-printing surfaces in close proximity thereto, and means carried by the frame for receiving the water discharged from said cooling device.

9. In a machine of the character described, the combination of a frame, a cooling device thereon having a perforated upper surface provided with longitudinal curved grooves, adapted to receive a cooling fluid, means for supporting plates on the cooling device with their non-printing surfaces in close proximity thereto, means carried by the frame for receiving the water discharged from said cooling device, and means located at the end of the cooling device and in line therewith for drying the inner surfaces of the plates.

10. A method of treating semi-cylindrical stereotype printing plates, which consists in finishing them and then wetting said plates on the rear concave surfaces to cool them while keeping the convex printing surfaces dry.

11. A method of cooling curved stereotype printing plates, which consists in causing water to run over a surface in continuous streams and bringing plates into such position that the inner surfaces thereof will come into contact with the water of said streams without wetting the printing surfaces thereof.

12. A method of cooling curved stereotype printing plates, which consists in causing water to run over a surface in a plurality of distinct parallel continuous streams and bringing plates into such position that the inner surfaces thereof will come into contact with the water without wetting the printing surfaces thereof, and thereafter drying said inner surfaces.

13. The method of cooling curved stereotype printing plates which consists in form-

ing a running sheet of water in a convex form of substantially the same curvature as that of the inside surface of the plate, and bringing the plate into such position that 5 the inner surfaces thereof will come into contact with the water.

In testimony whereof I have hereunto set

my hand, in the presence of two subscribing witnesses.

H. A. WISE WOOD.
